William D. Hall,
ATTORNEY

UNITED STATES PATENT OFFICE
2,639,403
STRAPPED MULTICAVITY MAGNETRON

Prescott D. Crout, Lexington, Mass., assignor, by
mesne assignments, to the United States of
America as represented by the Secretary of War

Application February 27, 1945, Serial No. 580,013

8 Claims. (Cl. 315—39)

1 This invention relates in general to magnetron oscillators, and more particularly to multiresonator magnetron oscillators operating in such a manner that the frequency of oscillations is dependent in part upon the transit time of the electrons between cathode and anode.

According to conventional magnetron construction, the tube comprises a cylindrical cathode and a plurality of cavity resonators which are part of the anode structure and the long axes of which are parallel to the cathode. These cavities are dispersed symmetrically about the cathode, and are directly coupled to the cathode-anode space by radially disposed slots, the holes and the slots forming a well known hole-and-slot anode structure which is placed in strong magnetic field parallel to the axis of magnetron. A coaxial line or a wave guide is usually electro-magnetically coupled to one of the cavities in order to extract radio frequency energy from the tube. When the anode is placed at a high potential with respect to the cathode, the orbital paths of the electrons within the cathode-anode space produce electrical oscillations in the cavity resonators.

When the above-described type of operation is used, the magnetron tends to oscillate at any given instant in one of various possible modes. Each mode has associated with it a particular electrical angle between adjacent cavity resonators, and a particular field configuration within the cavities. The mode in which a magnetron will oscillate depends on the plate voltage, the voltage waveform of the input, the magnetic field strength and the physical constants of the tube. It often happens that two or more modes are quite close to one another as far as small changes in the above-mentioned variables are concerned. Thus a magnetron may pass through several modes if its plate voltage is varied over wide limits, as is often the case. In order to increase the separation of these modes, and thus increase the stability of operation of the tube, the normally small mutual coupling between alternate cavities is increased by some form of conductors called straps which electrically connect similar areas of alternate resonator segments, their similar areas being near the inner tips of the segments. This method of construction is called strapping.

As is well understood in the art, however, a strapped magnetron is difficult and expensive to construct, because of the small dimensional tolerances which must be adhered to. In addition, the operation of the conventional magnetron

explained more fully later. Moreover the configuration of the coupling structure, together with some additional elements, is such that it performs a triple function, first—of coupling the resonators to the output circuit, second—of acting as a strapping means for the magnetron resonators to obtain more favorable mode separations and stability of operation in the selected mode, and third—the anode distributed reluctances are made to favor the desired pi-mode and block the remaining modes, thus enhancing the mode separation still further.

It is therefore an object of the present invention to provide a symmetrical magnetron output coupling for connecting a multiresonator anode of the magnetron to an output circuit, the coupling being equally coupled to each resonator of the anode.

Another object of this invention is to provide "tight," low resistance strapping system for a multiresonator magnetron.

An additional object of this invention is to provide a symmetrical magnetron coupling for connecting a multiresonator anode of the magnetron to an output circuit, this coupling performing a dual function, one of coupling the magnetron to the outgoing line or wave guide, and another of acting as low resistance strapping means for the magnetron resonators to obtain more favorable mode separation, and stability of operation in the selected mode.

Still another object of this invention is to provide a symmetrical coupling for a magnetron, which, because of its equal coupling to all resonators, may be used for external tuning of the output circuit, so that tuning of the magnetron is accomplished by varying the impedance of the output circuit and the "pulling" effect exerted by the output circuit impedance on the anode frequency.

Yet another object of this invention is to provide a multiresonator magnetron with wide mode separation between pi-mode and all other modes, this mode separation being obtained by providing preferred, low reluctance paths for magnetic fields due to the pi-mode resonance, and by blocking the distributed reluctance paths for the fields of other modes.

In accordance with the present invention there is provided a magnetron in which the internal structure is so arranged as to provide a common path for the fields of adjacent cavities. In this manner the fields of adjacent cavities are coupled tightly to one another, and the effect is the same as increasing the coupling between alternate cavities, with a concomitant increase in mode separation. In addition there is provided a type of output coupling which is symmetrical with respect to the individual cavities, resulting in increased efficiency and stability of operation.

These and other features of my invention will be more clearly understood from the following description and the accompanying drawings, in which:

Fig. 1 illustrates a perspective exploded view of the anode structure and its outgoing concentric line;

Fig. 2 illustrates a perspective view of the anode and its output coupling line, with their front portion cut away by a vertical plane passing through the axis of the magnetron;

Fig. 3 illustrates a side view of one type of suitable magnetron mounting and connections between the magnetron and one type of output circuit;

Fig. 4 and Fig. 5 illustrate two magnetic flux arrangements available with two possible tube structures;

Fig. 6 illustrates the electric field pattern for both arrangements of magnetic field; and

Fig. 7 illustrates the field pattern of the permanent magnet when the latter has a central bore.

Referring now to Figs. 1 and 2, the invention is illustrated by the way of an example, with a hole-and-slot magnetron which comprises a cylindrical cathode 18, and a hole-and-slot anode 12. While the invention is illustrated with a hole-and-slot anode, from the description that is to follow it will be obvious to those skilled in the art that the novel structures are equally applicable to magnetrons having other types of anodes, such as a vane-type anode, or any other type of symmetrical anode surrounding a centrally mounted cathode. The illustrated anode is an eight hole anode having holes 19 and slots 18.

The anode structure also includes bottom plate 11, a spider 14 having its legs 15 overlapping alternate anode segments, a spacer plate 16 having its fingers 17 overlapping those anode segments that the spider 14 does not touch, and a top plate 28. An output coaxial line 20 has its center conductor 21 connected to the center of the spider disk 14 and its outer conductor 22 electrically connected to the top plate 28 and thence through the fingers 17 of the spacer plate 16 to alternate anode segments.

At the bottom of anode block 12, there is incorporated a spacer plate 23 similar to spacer plate 16. Spacers 16 and 23 each effectively lengthen alternate anode segments in the axial direction. Thus spacer 23 and plate 11 act as low resistance straps for one set of anode segments. These may be either even or odd segments, as will be described later. If spacer 23 and plate 11 strap even segments, then the odd segments are strapped by spider 14 and plate 28 at the top.

Referring now to Fig. 2, which is a cutaway portion of the anode block 12 and the cathode 18, the cathode is shown as being placed symmetrically with respect to the anode segments, the filament 31 being inside and electrically insulated from the cathode. Spider 14 and spider legs 15, spacer plate 16 and spacer plate fingers 17, top plate 28, and inner conductor 21 of coaxial line 20 are all shown in their respective positions.

Referring now to Fig. 3, the magnetron 50 is mounted so that the field from the permanent magnet 51 is parallel to the cathode axis. The insulated heater leads 52 come up to the magnetron 50 in a sleeve 53 for which a hole 54 is cut in the lower pole piece 30 connected to the permanent magnet 51. The magnetron radiating fins 55 are mounted on the anode structure, which generally is operated at ground potential.

The output line 20, shown coaxial for example, comes out of the magnetron 50 in a direction parallel to the cathode, and so is brought out through a hole 56 in the upper pole piece 62 connected to the permanent magnet 51. One type of external tuning device is shown as an example, and comprises an elbow joint 57 and a length of line 61 in which a plunger 58 is moved along the line by a tuning knob 59 and screw 60, the position of said plunger determining the length of line 61 used for matching the magnetron to the load.

Referring now to the operation of the system, and to Fig. 1, the magnetron is of the multi-cavity transit-time type, with the cavities or cavity resonators 19 being coupled to the cathode-

anode space by means of slots 18. When a high potential is placed on the anode with respect to the cathode, and a strong magnetic field is applied parallel to the cathode axis, oscillations of the electrons occur within the cathode-anode space, and the energy from these oscillations is coupled to the cavities 19 by means of slots 18. The cavities 19 oscillate in the pi-mode, the ultra-high frequency magnetic field being parallel to the long axes of the cavities. The placement of the spider 14 and spacer plate 16 is such that there is a path for the magnetic flux between the adjacent cavities. Thus, the magnetic flux comes up through one cavity, passes over an anode segment, and then goes down through the next cavity. Two adjacent cavities are 180 electrical degrees apart and thus have magnetic fields in opposite directions. If the bottom spacer plate 23 is positioned rotatably about the axis of the tube, that is, in a staggered manner with respect to the upper spacer plate 16, the magnetic flux is seen to have a continuous winding path around the anode, this path being illustrated by a heavy dotted line 400 in Fig. 4. This flux therefore travels up through one cavity, over an anode segment, down through an adjacent cavity, through a path formed by an open space between plate 11, spacer 23, and the bottom surface of the anode 12, and up through the following cavity. This flux structure is called serpentine flux because it follows a serpentine path, the latter being illustrated in Fig. 4.

If this staggered arrangement of the spacers 16 and 23 is not used, and the openings in upper spacer 16 are directly above similar openings in the bottom spacer 23, the magnetic flux goes up one cavity, down an adjacent cavity and thence back to the first cavity. This flux arrangement is called ring flux, and its path is illustrated by a dotted line 500 in Fig. 5. For both the serpentine flux and the ring flux, the electric field in and between the cavities is the same, and is illustrated by lines 600 in Fig. 6.

The electric field structure of Fig. 6 is such that if a coaxial line is used for output coupling, the fundamental mode is excited in the line. If a wave guide is used for extracting energy, it may be circular, in which case the $TM_{0,1}$ mode is propagated in the guide. This mode is one in which the electric field in the guide is parallel to the axis, the magnetic field being transverse. Propagation in the guide will have to be facilitated, however, by a probe secured to the top of the spider and extending a slight distance into and along the axis of the guide.

In order to bring the coaxial line and heater leads out of the magnetron, holes 54 and 56 are placed in the pole pieces 30 and 62, which are connected to permanent magnet 51. The effect of these holes, referring to Fig. 7, is to increase the magnetic field in the center of the pole pieces. This distortion of the field does not have an undesirable effect upon the operation of the tube.

It has been stated in the objects of the invention that the disclosed output coupling also acts as an effective strapping means for the anode structure. This follows from the electrical connections between the spacers and the anode segments, between the spacers and the upper and lower plates 11 and 23, respectively, and the connections between the anode segments and the spider. The disclosed method of strapping is more effective electrically, and simpler mechanically, than the known strapping means, which ordinarily comprises two concentric metallic resonator anode with a plurality of radially dis-

rings, one ring being connected to the tips of odd resonators, while the other ring is connected to the tips of the even resonators. Generally speaking, the effectiveness of any strapping system depends on the low resistance, or low ultra-high frequency impedance, of each individual strap. Comparison of the mechanical features of the disclosed strapping with the most widely used concentric ring type of strapping reveals the fact that the resistances of the disclosed strapping links will be inherently much lower than the resistance of any ring type of strapping since the currents due to strapping in the disclosed system will flow along the disks 11 and 23 or spider 14. Since such paths will have much larger surfaces and shorter lengths than in the ring strapping, they also will have correspondingly lower resistance than the paths provided by the rings, which have limited available surfaces and longer paths for conducting the ultra-high frequency currents. Because of this low resistance strapping technique, the magnetron constructed in accordance with this invention will have superior mode stability.

The mode separations in the disclosed structure will be enhanced by the provision of the preferred paths for the magnetic fields created in the resonators when they oscillate in the pi-mode. These paths were fully discussed previously in the specification, and it may be recalled that they may have a serpentine or a loop configuration, depending upon the angular positions of the upper and lower spacers with respect to each other, as illustrated in Figs. 4 and 5. In either case, the pi-mode flux is provided with low, uniform reluctance paths throughout the entire configuration of the anode structure in both cases. It should be mentioned here that the conventional magnetron, and especially the end spaces above and below the anode, also provide uniform low reluctance paths for the magnetic fields of the above mentioned type. However, the known structure does not block the distributed reluctance paths for all other modes, and, as a consequence, all other modes, as a rule, are also provided with relatively low distributed reluctance paths for the magnetic fields generated by them. In the disclosed structure, while the paths for the magnetic fields due to pi-mode have low reluctance, the paths for all other modes are effectively blocked by the spacers 23 and 16 and covers 11 and 23, and especially by the radial extensions 17 of the spacers. Consequently, the magnetic fields of all other modes would encounter only high distributed reluctance paths. Such configuration of the reluctance paths for various modes, as it has been demonstrated by theoretical analysis of the anode structure of this type and by subsequent actual operation of the magnetrons constructed in accordance with the teachings of this invention, produces increased separation of the desired pi-mode from all other parasitic modes.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

I claim:

1. An ultra-high frequency magnetron multi-

posed anode segments, the resonators of said anode being defined in part by said segments, and metallic plates at both ends of said anode defining serpentine paths for the ultra-high frequency magnetic field generated in said resonators when said magnetron is operated in the pi mode.

2. An ultra-high frequency magnetron multi-resonator anode with a plurality of radially disposed anode segments, the resonators of said anode being defined in part by said segments, and a pair of metallic plate elements respectively connected to different alternate segments, said elements being respectively disposed at different ends of said anode, said resonators defining loop paths for the ultra-high frequency magnetic fields generated in said resonators when said magnetron is operated in the pi mode, each of said loop paths being down through one resonator, up through adjacent resonator, and across the respective ends of the anode segment separating the downward and upward paths of said fields.

3. An ultra-high frequency multiresonator anode with a plurality of anode segments, the even segments of said anode being higher than the odd segments at the upper end of said anode, and the odd segments of said anode being higher than the even segments at the lower end of said anode, a first metallic plate resting on said even segments only at the upper end of said anode, and a second metallic plate mounted upon the odd segments only at the lower end of said anode, whereby the ultra-high frequency magnetic fields generated in said resonators follow a serpentine path when said magnetron is operated in the pi mode.

4. An ultra-high frequency multiresonator cylindrical anode having upper and lower plane surfaces with a plurality of anode segments positioned between said upper and lower surfaces, a first spacer mounted on said upper surface, said first spacer having extensions resting on the even segments only of said anode, a first end-plate mounted on said first spacer, a second spacer mounted on said lower surface, said second spacer having extensions resting on the odd segments only of said anode, and a second end-plate mounted on said second spacer.

5. An ultra-high frequency magnetron multi-resonator anode with a plurality of anode segments, the odd segments of said anode being longer than the even segments of said anode at the upper and lower ends of said anode, and metallic plates resting on said odd segments and an output coupling including a coaxial line hav-

ing its inner conductor connected to the even segments only.

6. An ultra-high frequency magnetron multi-resonator anode having upper and lower plane surfaces with a plurality of anode segments positioned between said upper and lower surfaces, a first spacer mounted on said upper surface, said first spacer having extensions resting on the even segments only of said anode, a first end-plate mounted on said first spacer, a second spacer mounted on said lower surface, said second spacer having extensions resting on the even segments only of said anode, and a second end-plate mounted on said second spacer.

7. A magnetron multi-resonator anode having upper and lower plane surfaces with a plurality of anode segments positioned between said upper and lower surfaces, a first spacer mounted on said upper surface, said first spacer having extensions resting on alternate segments only of said anode, a first end plate mounted on said first spacer, a second spacer mounted on said lower surface, said second spacer having extensions resting on alternate segments only of said anode, and a second end plate mounted on the second spacer.

8. A strapped magnetron comprising a cathode, a multi-resonator anode with a plurality of radially disposed anode segments, and two spaced discs contiguous to said segments for strapping said segments, one disc being connected to the even anode segments only, and the other disc being connected to the odd anode segments only, said discs being coaxially mounted with the axis of said anode, the locus of the outer axial surface of said anode being a cylinder and the diameter of the disc connected to the even anode segments being substantially equal to the diameter of said cylinder.

PRESCOTT D. CROUT.
